UNITED STATES PATENT OFFICE.

EDWARD M. HEYLMAN, OF JANEVILLE, WISCONSIN, ASSIGNOR TO JANEVILLE MACHINE COMPANY, OF JANEVILLE, WISCONSIN, A CORPORATION OF WISCONSIN.

CORN-PLANTER.

SPECIFICATION forming part of Letters Patent No. 708,979, dated September 9, 1902.
Application filed June 5, 1902. Serial No. 110,382. (No model.)

To all whom it may concern:

Be it known that I, EDWARD M. HEYLMAN, of the city of Janesville, in the county of Rock and State of Wisconsin, have invented certain new and useful Improvements in Corn-Planters, of which the following is a specification.

This invention relates to reels for automatically winding and unwinding check-row wire. The principal object of the invention is to provide means for automatically moving the wire along the reel as it wound up, so that the wire will be deposited on the reel in uniform layers, and another object is to provide an efficient simplified friction-controller for the reel.

The invention is exemplified in the structure hereinafter described, and it is defined in the appended claims.

In the drawings forming part of this specification, Figure 1 is a plan of so much of a planter as is needed to explain my invention. Fig. 2 is an elevation of the wire-guide mechanism.

The rear frame of a planter is shown at 1, an axle-shaft at 2, and a covering-wheel at 3. A seat-bar 4 is connected at its front end with the planter-frame, and it extends obliquely upward and rearward above the axle-shaft 2. A bracket 5 is secured to a side bar of the planter-frame, and it provides a journal for a worm-wheel 6. A worm 7 is fastened onto shaft 2 in mesh with wheel 6, and it provides means for imparting the motion of the covering-wheel to the worm-wheel. A bracket 11 is secured to the seat-bar 4 above shaft 2. A guide-arm 9 is pivoted to bracket 11, and an eye 10 is formed in the lower swinging end of the guide-arm. A pitman 8 is pivoted in the worm-wheel, off the center thereof, and connected pivotally with the guide-bar 9. The reel-shaft 12 is journaled in brackets secured to the planter-frame and is located beneath the seat carried by bar 4. A chain 20 transmits motion from a sprocket-wheel 19 on the axle-shaft to a sprocket-wheel 21, fixed on the shaft of the reel. The reel is mounted loosely on the shaft. A cone 15 is fixed to or formed on the reel-shaft adjacent to a side of the reel. A hooked lug

14 is formed on a side of the reel, off the center thereof. A brake-arm 16 has one of its ends in engagement with lug 14, its central part engaging the cone 15 and its other end projecting beyond the shaft on the side thereof opposite lug 14. A bolt 17 extends through the swingable end of the brake-arm, and a spring 18 bears against a washer on the rod and against the arm.

As the planter travels forward motion is transmitted to shaft 12 through the chain-gearing, and the brake-arm is pressed against cone 15 with sufficient force to compel the reel to travel with the shaft under ordinary circumstances, while permitting slippage of the reel on the shaft when tension on the wire becomes excessive. Preparatory to reeling up, the wire 22 is passed through the eye 10 of the guide-arm 9 and attached to the reel. Then as the wire is wound onto the reel the worm slowly rotates wheel 6, imparting an oscillating motion to arm 9 through pitman 8 and gradually moving the wire from end to end of the reel. The motion of the guide-arm is so timed with relation to the rotation of the reel that the wire is wound onto the reel in approximately uniform layers.

I claim—

1. The combination with the axle-shaft of a planter and a reel journaled crosswise of the planter-frame, of a worm on the axle-shaft, a worm-wheel in mesh with the worm, a wire-guide and a pitman connecting the wire-guide with the worm-wheel.

2. The combination with the axle-shaft of a planter and a reel journaled crosswise of the planter-frame, of a worm on the axle-shaft, a worm-wheel in mesh with the worm, an oscillating arm carrying a wire-guide in its swinging end and a pitman connecting the worm-wheel with the arm.

3. The combination with the axle-shaft of a planter and a reel journaled crosswise of the planter-frame, of a seat-bar above the axle-shaft, an arm pivotally connected with the seat-bar, a wire-guide in the swinging end of the arm, a worm on the axle-shaft, a worm-wheel in mesh with the worm and a pitman connecting the worm-wheel with the arm.

4. In a reel for check-row wire, the combi- 103

uation of a reel-shaft, a reel journaled loosely on the shaft, a friction-bearing on the reel-shaft adjacent to an end of the reel, a hooked lug on the end of the reel in proximity to the friction-bearing on the shaft, a friction-arm having one end in pivotal engagement with the hooked lug and also having its intermediate part in contact with the friction-

bearing of the shaft, and a spring forcing the opposite end of the arm toward the reel. ^{to}

In testimony whereof I sign my name in the presence of two subscribing witnesses.

EDWARD M. HEYLMAN.
